APPARATUS FOR TREATING SYNTHETIC FIBERS

Clarence B. Moss, Elizabethton, Tenn., assignor to Synthane Corporation, Oaks, Pa., a corporation of Delaware

Application April 13, 1950, Serial No. 155,672

5 Claims. (Cl. 242—110)

1

The present invention relates to the treatment of synthetic textile fibers, particularly nylon and the like, and to apparatus for facilitating controlled shrinking of such fibers preparatory to other operations incident to their use, for example in the manufacture of textiles.

As is well known new nylon fiber when subjected to certain treatments exhibits a tendency to shrink to a degree different from, and usually greater than, other fibers under the same treatment. Consequently when nylon fiber without preliminary shrinking treatment is blended with other fibers, for example rayon, in the subsequent manufacture of yarn and textile fabrics and the latter then exposed to conditions causing shrinkage, the fibers shrink unequally which under most conditions is objectionable.

Therefore efforts have been made to effect a preliminary controlled shrinking of nylon fiber to reduce its tendency to thereafter shrink unequally with other fibers with which it may be blended and to retain only that capacity for further shrinking which will result in the nylon and such other fibers shrinking equally and uniformly when made into yarn and/or fabric.

However, as far as I am aware these efforts have not afforded a satisfactory method of attaining the desired equality of shrinking capacity of the different fibers when blended or resulted in the development of apparatus for suitably controlling the shrinking of nylon or like fiber to reduce to a desired predetermined value its capacity for further shrinkage.

It is therefore a principal object of the invention to provide a method of and apparatus for effecting controlled shrinkage of textile fiber such as nylon whereby a predetermined proportion of its initial capacity for shrinking may be eliminated and a residual proportion thereof retained to the end that it may shrink uniformly with other fibers when thereafter blended therewith in the manufacture of yarn and/or fabric.

A further object is to provide a method of and means for treating a textile fiber operative to permit controlled and substantially uniform shrinking thereof without thereafter requiring rewinding of the fiber to enable it to be utilized in modern machines for the manufacture of yarn.

Other objects, purposes and advantages of the invention will hereafter more fully appear or will be understood from the following description of a preferred mode of practising the method thereof with the aid of one embodiment of apparatus comprehended by the invention as illus-

2

trated in the accompanying drawings in which:

Fig. 1 is a view partly in side elevation and partly in axial section of one unit of said apparatus;

5 Fig. 2 is a side elevation on a smaller scale of a nylon fiber package made with the aid of said unit;

Fig. 3 is a transverse section of said package on line 3—3 in Fig. 2 but on the same scale as 10 Fig. 1;

Fig. 4 is an exploded side elevation, partly in axial section, on the scale of Fig. 1 showing said package after the fiber has been shrunk together with means for supporting it on the creel of a 15 spinning machine or the like; and

Fig. 5 is a transverse section on the line 5—5 in Fig. 4 but on a larger scale than any of the preceding figures.

Referring now more particularly to the drawings the apparatus therein illustrated will be described initially to fully disclose its structure and character while its functions in attainment of the objects of the invention will later more specifically appear from the succeeding description of my novel method of treating fibers with the aid of said apparatus though it will be understood other apparatus may satisfactorily be employed in the practice of said method if desired.

Thus the apparatus as illustrated in Figs. 1—3 20 comprises a barrel unit including a pair of concentric substantially cylindrical sleeves 1, 2 which may conveniently be formed from pieces of laminated synthetic resinous tubing of appropriate diameter. Each of these sleeves is provided with a slot extending the entire length of its wall parallel to its axis, the sides of the slot 3 in inner sleeve 1 substantially paralleling radial planes while the outer sleeve adjacent its slot 4 is preferably feathered to a fairly thin edge 25 continuous with and substantially tangent to its inner surface whereby when the sleeves are telescoped together with their slots out of circumferential alignment the outer surface of the outer sleeve adjacent slot 4 slopes inward toward the outer surface of the inner sleeve and the sleeves cooperate to provide a smooth uninterrupted substantially cylindrical outer surface for the unit as a whole; the inner sleeve at each end has a beveled inner surface 5 conforming respectively 30 to corresponding surfaces of supporting mechanism hereafter to be described. Supplementing the natural resiliency of the sleeves, in the inner surface of inner sleeve 1 spaced inwardly from each end is a circumferential groove 7 receiving an arcuate spring 8 desirably formed

from corrosion resistant spring strip such as stainless steel or the like biased circumferentially against the inner sleeve to resist centripetal compression of the barrel unit.

This unit is adapted to serve as the barrel or body of a spool for receiving the fiber to be treated, the spool also including a pair of circular laminated synthetic resinous heads 15, 16 each having a groove 17 in its inner face for reception of the sleeve ends, the inner sides of said grooves being tapered as at 18 to generally correspond to the bevels 5 of the latter. A tubular axial spindle 19 for the spool may be permanently fixed to head 15 and removably threaded into head 16 whereby these parts may be readily assembled with and dissembled from the sleeves. The spindle and heads thus provide means for mounting the barrel unit in winding mechanism (not shown) whereby a quantity of fiber F may be wound upon it, for example sufficient to provide thereon a package or cake extending axially in opposite directions to just short of the sleeve ends and up to about an inch or less in radial thickness, after which the spool heads and spindle may be detached and used with another barrel unit.

Other means provided for supporting the package, consisting of the barrel unit and fiber when formed as just described, during and after a shrinking treatment comprise a pair of somewhat smaller circular heads 20, 21 each having an annular groove 23 in its inner face and likewise preferably made from laminated synthetic resinous stock. The inner diameter of these grooves 23 preferably substantially corresponds to the inside diameter of inner sleeve 1 when the latter has been compressed circumferentially against the bias of springs 8 sufficiently to bring the sides of slot 3 together or substantially so and the outer diameter of the grooves substantially corresponds to the outside diameter of outer sleeve 2 when it has been compressed against the inner sleeve in this condition and its slot 4 thus contracted to narrower width than it normally assumes when the unit is relatively unstressed. Desirably slot 3 is proportioned to permit circumferential contraction of the barrel unit to the degree requisite to allow a predetermined amount of shrinking of fibers wound thereon to bring the sides of the slot together.

A tubular axial spindle 25 connecting heads 20, 21 may be cemented or otherwise fixed in head 20 while bayonet slots 26 in its free end are provided for reception of a pin 27 which extends across an axial bore 28 in head 21 whereby the latter may be removably secured to the spindle, a disk 30 biased by a spring 31 in this bore yieldingly maintaining pin 27 properly seated in slots 26.

In the employment of above described apparatus for the practice of the method of my invention sleeves 1, 2 are disposed in telescoped concentric relation with their slots 3, 4 substantially diametrically opposed or at least not in alignment and assembled with heads 15, 16 held together by spindle 19; the entire spool assembly is then mounted in any suitable apparatus appropriate for rotating it or otherwise winding a quantity of fiber upon it, grooves 17 in the heads receiving respectively the ends of both sleeves fairly snugly when they are free of external stress. Desirably these grooves are so proportioned that to enter them the outer sleeve must be slightly compressed against the inner one, the beveled ends of the latter then lying closely against the

tapered inner sides of the grooves to resist further contraction of the sleeves during winding of fiber on the barrel unit while the heads are firmly held assembled therewith.

After a cake of the desired size has been wound on the spool heads 15, 16 and spindle 19 may be removed from the sleeves and the fiber package, consisting of sleeves 1, 2 with springs 8 in their grooves and the surrounding cake of fiber, is then subjected to a shrinking treatment, for example one which includes holding it for an appreciable period in a steam bath. As the fiber shrinks in consequence of this treatment it gradually compresses the sleeves circumferentially until the sides of slot 3 engage each other, after which further shrinking is effectively resisted by the incompressibility of the sleeves and the width of slot 3 is therefore calculated to permit that degree of shrinking desired, thus rendering it unnecessary to attempt to control it by careful timing of the steam treatment or otherwise.

After slot 3 has been substantially closed and slot 4 of course simultaneously correspondingly contracted as a result of shrinking of the fiber the package is placed between heads 20, 21 and the latter secured together with the aid of spindle 25, the grooves in the heads receiving the ends of the contracted sleeves fairly snugly to restrict their expansion during unwinding of the shrunk fiber therefrom in a subsequent spinning operation or the like. The package may therefore be placed on a creel or otherwise positioned for unwinding and the shrunk fiber withdrawn therefrom in the manner normally employed for utilizing fibers of this character in textile manufacture, and it will be understood that although the fiber after shrinking and before unwinding is maintained under stress due to the opposition to compression exerted by the sleeves, assisted by springs 8, this opposition is ineffective to seriously disturb the lay of the fiber even when all but relatively few turns have been unwound since the grooves in heads 20, 21 hold the sleeves at least partially compressed until the heads are ultimately removed from the sleeves and the latter thus cannot fully expand during unwinding of the fiber. Their expansion to relatively unstressed condition follows as a matter of course, however, after the fiber has been unwound and heads 20, 21 removed from the sleeves following disengagement of pin 27 from its bayonet slots in spindle 25.

It will be understood that if desired heads 15 and 20 may be provided with spaced diametrically opposed sockets 35, 36 respectively for reception of corresponding studs of winding or braking mechanism or any other suitable means utilized for effecting and/or controlling rotation of the barrel unit when it is assembled with either pair of heads or equivalent supporting apparatus and, further, that the mechanism employed for either winding the fiber thereon or unwinding it therefrom forms no part of the invention, being usually similar to that in general use in the textile arts for winding and unwinding fibers and yarns.

It will moreover be understood that while I have herein described with considerable particularity one embodiment of apparatus constructed in accordance with the invention and have explained in detail the use thereof in the practice of my method, I do not desire or intend thereby to be limited or confined in any way as changes and modifications in the form, structure, arrangement and relationship of the several parts

of the apparatus as well as in the mode of practising the several steps of my novel method will readily occur to those skilled in the art and may be employed if desired without departing from the spirit and scope of the invention as defined in the appended claims.

Having thus described my invention, I claim and desire to protect by Letters Patent of the United States:

1. Apparatus for controlling shrinkage of textile fiber during a shrinking operation comprising a pair of telescoped substantially tubular sleeves each having a slot extending from end to end thereof, the slots being circumferentially non-aligned, the slot in at least one of the sleeves being of width such that its edges are brought into substantial interengagement circumferentially when fiber wound on the outer sleeve and subjected to a shrinking operation has shrunk to a degree less than its capacity for shrinking under uncontrolled shrinking conditions.

2. Apparatus as defined in claim 1 in which the inner sleeve has spaced circumferential grooves in its inner surface, and arcuate springs seated in said grooves biased circumferentially against said sleeve to resist centripetal contraction thereof.

3. Apparatus as defined in claim 1 in which the edges of the slot in the inner sleeve lie substantially in radial planes and the outer sleeve is beveled substantially tangentially to its inner surface adjacent the edges of its slot.

4. Apparatus as defined in claim 1 in combination with a pair of substantially circular supporting heads having circular grooves receiving respectively the ends of the sleeves, the inner walls

of said grooves being tapered and the inner surface of the inner sleeve being beveled substantially in correspondence to the taper of said groove adjacent the sleeve ends, and means for releasably holding the heads axially in assembled relation with the sleeves whereby the tapered walls of said grooves cooperate with the beveled inner surfaces of the inner sleeve to resist circumferential contraction of the sleeves.

5. Apparatus as defined in claim 1 in combination with a pair of substantially circular supporting heads having annular grooves receiving respectively the ends of the sleeves, the outer walls of said grooves corresponding substantially to the outer diameter of the outer sleeve when the edges of the slots in the sleeves are of less than normal width thereby to inhibit circumferential expansion of the sleeves when the latter are relieved of centripetal stress of shrunk fiber wound on the outer sleeve, and means for releasably holding the heads in assembled relation with the sleeves.
